CLAIM

The ornamental design for a window seal for portable air conditioner, as shown and described.

DESCRIPTION

FIG. 1 is a front view of a window seal for portable air conditioner showing my new design.

FIG. 2 is a rear view of a window seal for portable air conditioner.

FIG. 3 is a left side view of a window seal for portable air conditioner.

FIG. 4 is a right side view of a window seal for portable air conditioner.

FIG. 5 is a top view of a window seal for portable air conditioner, shown enlarged in scale.

FIG. 6 is a bottom view of a window seal for portable air conditioner, shown enlarged in scale.

FIG. 7 is a perspective view of a window seal for portable air conditioner.

FIG. 8 is an enlarged view of a window seal for portable air conditioner taken from the circle part in FIG. 1.

FIG. 9 is an enlarged view of a window seal for portable air conditioner taken from the circle part in FIG. 2.

FIG. 10 is an enlarged view of a window seal for portable air conditioner taken from the circle part in FIG. 4; and,

FIG. 11 is an enlarged view of a window seal for portable air conditioner taken from the circle part in FIG. 7.

Any shading and cross-hatching are not features of the design but are utilized to illustrate the surface contours of the window seal for portable air conditioner design in the drawings.

The broken lines shown in the figures are for the purpose of illustrating portions of the air conditioner and form no part of the claimed design.

1 Claim, 11 Drawing Sheets
